UNITED STATES PATENT OFFICE.

ALBERT O. BUCKIUS, OF CHICAGO, ILLINOIS, ASSIGNOR TO CHARLES A. TAYLOR, OF SAME PLACE.

TRUNK-FASTENING.

SPECIFICATION forming part of Letters Patent No. 373,879, dated November 29, 1887.

Application filed February 19, 1887. Serial No. 238,219. (Model.)

To all whom it may concern:

Be it known that I, ALBERT O. BUCKIUS, a citizen of the United States, residing at Chicago, in the county of Cook and State of Illinois, have invented certain new and useful 5 Improvements in Trunk-Fastenings, of which the following is a description.

My invention relates to certain improvements in trunk-fastenings whereby the construction is greatly simplified and whereby the hasp can be opened and maintained in an open position at a certain angle while the bolt extending down from the top plate is released and withdrawn or returned to be locked by 15 the action of said hasp, substantially as hereinabove described, and as illustrated in the drawings, in which—

Figure 1 shows perspective views of the top plate and the body-plate of my improved trunk- 20 fastening. Fig. 2 is a transverse vertical section thereof, showing the two plates together; and Fig. 3 shows a modification of the spring used in conjunction with the hasp in the body-plate.

Reference being had to the drawings, A represents a top plate, which is secured to the lid of a trunk, so that the bolt *a* thereof extending vertically and centrally down from its lower edge projects below the edge of the trunk-lid. 25 This bolt *a* is provided with an outward projection, *b*, near its extremity, as shown, whereby the hasp of the fastening attached to the body of the trunk in register therewith can close over and secure the same, as will hereinafter more fully appear. Besides this bolt *a*, there projects down from the plate A, on either side of the same, the dowels *b' b'* which enter 30 corresponding sockets in the top edges of the vertical ridges *c c* of the body-plate C, and serve to direct the bolt *a* between the ridges *c c* when the lid of the trunk is closed onto the body thereof.

The ridges *c c* of the body-plate extend parallel to each other a suitable distance, whereupon they merge into a common pocket, *d*, having a transverse opening, *d'*, in it, as shown. 45

Pivoted by means of trunnions *e e*, projecting laterally from its lower corners and journaled in recesses *e' e'* in the under surface of 50 plate C, is the hasp D. This hasp conforms in lateral dimensions to the space between ridges

c c, and its upper portion is provided with a vertical slot, E, through which, when bolt *a* of the top plate lies between said ridges and the hasp is oscillated in against the plate, the 55 projection *b* projects.

Projecting outward from a point centrally between ridges *c c*, which, when the lid of the trunk is closed, the bolt *a* of the top plate just touches, is a lug, F. This lug F projects 60 outward to the plane of the outer surfaces of ridges *c c*, and has projecting toward the lower end of plate C a flange, *f*. The slot E of hasp D is of such length vertically that the lug F, when the hasp is closed, projects through said 55 slot just below projection *b*.

Secured centrally and longitudinally to the inner surface of hasp D is a flat spring, G, which extends below the pivotal point of the hasp (at which point it is made thicker, so as 70 to bow said spring) to and through the transverse opening *d'*, where its lower end rests in a depression or rabbet, *g*, adjacent to said opening *d'*, as shown. Thus it will be observed by reference to the drawings that when 75 the hasp is oscillated outward the spring G is bowed to such an extent that its flexibility has a tendency to restore it to its original position the moment the hasp is released. It is desirable, however, when the hasp is oscillated outward to maintain it at about the angle shown while bolt *a* is being withdrawn or advanced 80 toward plate C and into position to be locked. I accomplish this by bending spring G at about the lower terminus of slot E inward at about 85 an angle of forty-five degrees to the back of the hasp, making a spring arm, *h*, the extremity of which is shaped so as to form a transverse depression on the upper surface, as shown in Fig. 2. The flange *f* of lug F is of 90 such projection and the depression of arm *h* of such shape that when the hasp is oscillated outward the said arm bears against the flange *f* until the depression in its end is reached, when it snaps over the outer edge of said 95 flange, holding the hasp sufficiently secure to prevent it of its own volition returning to its original position and maintaining it open, as shown. By pressing slightly upon the hasp the spring-arm *h* releases its hold on flange *f*, 100 and the hasp, by reason of spring G, returns to its original position.

If desired, any of the usual methods or arrangement of springs for returning and keeping the hasp in its original position may be resorted to and used in conjunction with spring-5 arm *h*. It is also apparent that spring *G* may be used in combination with other devices for maintaining the hasp in an open position than the arm *h* described. I prefer, however, to use them together. When spring *G* and spring-10 arm *h* are used conjointly, they may be made of separate pieces of material or all in one piece.

I do not wish to be confined to the use of arm *h* constructed as described, for other shapes 15 may be adopted which would operate equally as well. For instance, the arm could be L-shaped and the end of the portion thereof parallel to the back of the hasp made to snap into a transverse groove in the lug *F* when the 20 hasp has been oscillated outward to a certain angle; or, again, the arm might be perfectly straight with sufficient obliquity to make its pressure against the adjacent surface of lug *F* create sufficient friction to maintain the hasp 25 at the angle desired.

It is apparent that the projection *b*, instead of projecting from the bolt *a* of the top plate, may be transferred to the end of the hasp *D*, and when said hasp is closed to lock the bolt 30 *a* enter an opening therein in register with said projection *b*. As such construction would be but a modification of my invention as heretofore described, I desire to cover it.

What I claim as new is—

1. In a trunk-fastener, the combination, with 35 plate *C*, provided with a lug, *F*, of hasp *D*, having spring-arm *h*, the free end of which is adapted to engage said lug, substantially as set forth.

2. In a trunk-fastener, the combination, with 40 plate *C*, having a lug, *F*, provided with a flange, *f*, of a hasp, *D*, provided with a spring-arm, *h*, secured to the back thereof, said arm having a transverse depression in or near its extremity adapted to engage said flange, sub-45 substantially as set forth.

3. In a trunk-lock, the combination, with 50 plate *C*, having a lug, *F*, and hasp *D*, pivoted therein, of a spring, *G*, secured to the back of said hasp, having its upper end in register therewith, bent at right angles to said hasp, as described, and having its lower end extend down past the point of oscillation of said hasp to and secured in said plate *C* below the pivotal point of said hasp. 55

4. The combination, with plate *A*, having a bolt, *a*, with a projection, *b*, on its end, extending downward therefrom, of plate *C*, lug *F*, projecting therefrom, having a spring-actuated hasp, *D*, with a slot in its upper end, and 60 spring-arm *h*, secured to the back of said hasp and extending at right angles therefrom in register with lug *F*, as set forth.

ALBERT O. BUCKIUS.
